RELEASABLE SUCKER ROD CONNECTION

Russell Livergood, Houston, Tex.

Application December 5, 1938, Serial No. 244,010

5 Claims. (Cl. 103—226)

This invention relates to pumps and more specifically to a releasable connection whereby the sucker rod may be disconnected from or connected to the plunger within the well so that the sucker rod and tubing may be separately removed.

When it is desired to withdraw from a well the tubing string in which the usual sucker rod and pump plunger are positioned, it is advantageous to disconnect the sucker rod from the pump plunger and to remove such rod separately from the tubing string. If it is desired to remove the plunger and sucker rod before pulling the string, difficulty is frequently encountered because of the destructive effect produced upon the plunger in pulling such plunger through the tubing string together with the sucker rod.

It is a general object of the present invention to provide a practical device for attaching and detaching the sucker rod and the plunger reciprocated thereby in order to avoid indicated difficulties.

It is also an object to provide a releasable connection between parts of the reciprocating assembly of a well pump, such connection being so constructed that release will take place automatically upon lifting of the assembly to a predetermined level.

It is also an object to provide a positive yet releasable connection between the sucker rod and the pump plunger.

Still another object is to provide a releasable connection which is released by cooperation with an inwardly extending projection within the tubing string when the sucker rod and plunger assembly is moved to make engagement with such projection.

Other objects together with the foregoing will be apparent from the following description taken in connection with the drawing in which:

Fig. 1 is a vertical section through a construction embodying the invention and in which the parts of the reciprocating assembly are interconnected.

Fig. 2 is similar to that shown in Fig. 1 but is shown in partial section and illustrates the relative position of parts at the instant of disconnection of the sucker rod from the remainder of the assembly.

As illustrated in the drawing the invention comprises a tubing string 1 including sections 2 and 3 interconnected by means of a special coupling 4 having an inward annular projection 5 formed by the downwardly depending surface 6 and a downwardly facing shoulder 7.

The section 3 serves as a pump cylinder and receives the pump plunger 10 which is placed therein preliminary to the lowering of the tubing string into the well. As has already been indicated it is the purpose of the invention to provide a releasable connection between the plunger 10 and the sucker rod 11 so that the sucker rod may be lowered within the tubing string 1 after such string has been placed in the desired position within the well. Likewise the construction is designed to enable removal of the sucker rod 11 preliminary to withdrawal of the tubing string 1 from the well.

In order to provide the desired connection the lower end of the sucker rod 11 is provided with a section 12 of special configuration, such section being attached to the sucker rod 11 by means of the threads 13. The lower end of the section 12 is provided with a head 15 which is formed by downwardly and inwardly tapered face 16 which merges into downwardly tapered portion 17 terminating in a rounded end extremity 18.

A connector generally designated as 20 is attached to the plunger 10. This connector includes a bushing 25 which is counterbored at its upper end and slotted at 26 to provide resilient fingers 27 having tapering inner and outer faces 28 and 29 at their upper ends to serve a purpose that will be more fully apparent.

Below the counterbore the bushing 25 is reduced in cross section to form a downwardly facing shoulder 30. The lower end of the reduced portion terminates in a stem 31 through which the bushing is connected to the plunger 10.

A sleeve 40 surrounds the bushing 25 and has an inwardly extending flange 41 at its lower end which slides over the reduced portion of the bushing 25 and engages the shoulder 30 to limit upward movement of the sleeve relative to the bushing. At its upper end the sleeve 40 is provided with an inner tapering surface which is complementary to the outer tapered surface on the fingers 27. It is believed apparent that whenever the sleeve 40 surrounds the bushing 25 as shown in Fig. 1, the fingers 27 are restrained against outward movement by virtue of the complementary tapered surface on these members. This is the normal relative position of the bushing 25 and the sleeve 40 since the sleeve is constantly urged upwardly against the shoulder 30 by means of a spring 42 surrounding the bushing 25 and held in tension by means of a collar 30 fixed on the stem 31 by any suitable means such as threads 43 and set screw 44.

Within the counterbore in the bushing 25 there is positioned a slip member 50 which, similar to the bushing 25, is also counterbored and slotted to provide fingers 51 having inner and outer tapered faces which are complementary to the surface 28 on the bushing 25 and the surface 17 on the head 15. This slip member is provided with an opening at its lower end to receive a cap screw 55 having a threaded connection 56 in the bottom of the counterbore in the bushing 25. A spring 57 surrounds the cap screw 55 and constantly urges the slip member 50 upwardly so that the fingers 51 are held in their innermost position.

The mode of operation and the advantages attained by use of the construction just described are believed apparent from the foregoing description. As already indicated the plunger 10 will be positioned within the tubing section 3 and lowered into the well with the tubing string. The section 12 is then attached to the sucker rod and is lowered into the well. When the head 15 reaches the collar 4 it is guided to the center of the tubing string by virtue of the tapered surface 6 and also tapered surface 19 on the bushing 25. The head 15 therefore makes engagement with the slip member 50 which is urged downwardly against the force exerted by the spring 57. As the slip member 50 passes downwardly from the tapered surface 28 of the bushing 25 the force exerted thereon by the head 15 will cause the fingers 51 to move outwardly and permit the head 15 to enter the slip member. As soon as the head enters the slip member the face 18 engages the conical surface 19 and the slip member 50 moves upwardly under the influence of the spring 57 to tightly wedge between the tapered surface 28 and the surface of the head 15. In this manner a rigid connection between the connector 20 and the sucker rod is effected, and acts in the same manner as the usual connection of the sucker rod string to the pump plunger so long as reciprocation of the assembly takes place below the coupling 4 in the tubing string.

When it is desired to disconnect the sucker rod from the pump plunger 10, the sucker rod string is elevated until the sleeve 40 engages the shoulder 7. Further lifting of the assembly causes compression of the spring 42 and the bushing 25 moves upwardly relative to the sleeve 40. Such upward movement of the bushing 25 together with the slip member 50 therein releases the fingers 27 so that the head 15 causes both the fingers 51 and the fingers 27 to move radially outward, whereby the connection between the sucker rod and the pump plunger is released. The relative position of parts when such release takes place is illustrated in Fig. 2.

Broadly the invention comprehends a releasable connection whereby a sucker rod may be connected to or disconnected from a pump plunger so that the sucker rod and tubing string within a well may be separately removed therefrom.

What is claimed is:

1. In a device of the class described, a tubing string, an assembly including a pump plunger

and a sucker rod within said string, a head on the lower end of said sucker rod, an inwardly extending projection in the string adapted to guide the head centrally of the string as the head moves past the projection, and a releasable connection between the sucker rod and the plunger, said connection including a member adapted to engage said projection and a fingered bushing movable from within the member to expand and release the sucker rod when the assembly is lifted to a predetermined level within the string.

2. In a pump assembly, a plunger, a sucker rod having a head at its lower end, a bushing attached to the plunger and having fingers adapted to effect engagement with said head, a sleeve surrounding said bushing and slidably longitudinally thereof, and resilient means normally holding said bushing and sleeve in concentric relation to hold the fingers in engaging position.

3. In a pump assembly, a cylinder, a plunger therein, a sucker rod, means attached to said plunger and including resilient fingers for engaging the end of the sucker rod whereby the sucker rod and plunger comprise a composite assembly, means normally holding the fingers in engagement with the sucker rod, and means extending inwardly from the walls of said cylinder for engaging said last mentioned means to disconnect the sucker rod when the assembly has moved to a predetermined level within the cylinder.

4. In a device of the class described, a tubing string, an assembly including a pump plunger and a sucker rod within said string and having a head on its lower end, an inwardly extending projection in the string adapted to guide the head centrally of the string as the head moves past the projection, a releasable connection between the sucker rod and plunger, said connection comprising a member adapted to engage said projection as the assembly is moved upwardly within the string, a fingered member movable from within the first mentioned member, said fingered member having an upwardly converging inner surface therein, and a slip member movable within said bushing and having spring fingers with outer surfaces adapted to engage said tapering face whereby the head is rigidly engaged therein.

5. In a device of the class described wherein a releasable connection is provided between a pump plunger and a head on the lower end of a sucker rod, the combination of a bushing attached to the pump plunger and having fingers adapted to move radially thereof, a sleeve surrounding said bushing and slidably longitudinally thereof, resilient means normally holding said bushing and sleeve in concentric relation to hold the fingers in fixed position, said fingers having upwardly converging inner surfaces therein, a slip member within the bushing and having an outer surface adapted to engage said converging surface, and means resiliently supporting the slip member within the bushing so that the head may move into the bushing and enter the slip member to be rigidly engaged thereby.

RUSSELL LIVERGOOD.
